UNITED STATES PATENT OFFICE.

GEORGE H. KNUPP, OF WAPAKONETTA, OHIO, ASSIGNOR TO HIMSELF AND
HARVEY BROKAW, OF SAME PLACE.

IMPROVEMENT IN WATCH-ESCAPEMENTS.

Specification forming part of Letters Patent No. **150,766**, dated May 12, 1874; application filed
February 7, 1874.

To all whom it may concern:

Be it known that I, GEORGE H. KNUPP, of Wapakonetta, in the county of Auglaize and State of Ohio, have invented a new and useful Improvement in Watches, of which the following is a specification:

A means heretofore used for causing the vibration of balance-wheels of lever-escapement watches, is a pin fixed vertically in a disk attached to the under side of such wheels, and adapted to engage with the notched or slotted end of the lever. But this arrangement is open to serious objection, chiefly in that the aforesaid pin is liable to become permanently disengaged from the notch in the lever. To prevent this result, which is technically termed "overbacking," is the great object of my invention. And to this end I provide the notched end of the escape-lever with curved arms so arranged as to guide the pin of the balance-wheel back into the notch when overbacking occurs, and thus immediately restore the normal operation or function of the parts.

In the accompanying drawing, Figure 1 is a view of the balance-wheel and improved forked lever, showing the ruby-pin and guards.

Fig. 2 is an edge view of the same.

Similar letters of reference indicate corresponding parts.

A is the balance-wheel. B is the balance-wheel post. C is the plate or disk on the balance-wheel post. D is the ruby-pin in the plate C. E is the lever, on the end of which are formed two circular guards, F F, having between them a small slot, G, in which the ruby-pin works. The guards curve or round outward, directly from the notch or open slot, so that the pin D is readily guided back into the latter (without jar or strain of any of the parts) whenever it leaves its proper arc of vibration.

This construction enables the ordinary banking-pins (for limiting the throw of the lever) to be dispensed with.

Having thus described my invention, I claim as new and desire to secure by Letters Patent—

The lever E, having the arms F F extending directly from the notch, and curved around the balance-staff, their outer ends being in the path of the ruby-pin, and serving as a banking therefor.

GEORGE H. KNUPP.
